PILLOWCASE OR SIMILAR ARTICLE

Edwin I. Cohen, New York, N. Y.

Application December 29, 1948, Serial No. 150,421

Term of patent 3½ years

(Cl. D92—26)

To all whom it may concern:

Be it known that I, Edwin I. Cohen, a citizen of the United States of America, residing in New York city, county of New York, and State of New York, have invented a new, original, and ornamental design for a Pillowcase or Similar Article, of which the following is a specification, reference being had to the accompany drawing, forming part thereof, wherein,

The rear of the pillowcase is identical in appearance to the front shown.

I claim:

The ornamental design for a pillowcase or similar article, substantially as shown and described.

EDWIN I. COHEN.
